His Attorney.

UNITED STATES PATENT OFFICE.

THOMAS K. CONWAY, OF WATERBURY, CONNECTICUT.

NECKTIE-FASTENER.

SPECIFICATION forming part of Letters Patent No. 425,865, dated April 15, 1890.

Application filed January 24, 1890. Serial No. 337,922. (No model.)

To all whom it may concern:

Be it known that I, THOMAS K. CONWAY, a citizen of the United States, residing at Waterbury, in the county of New Haven and State 5 of Connecticut, have invented certain new useful Improvements in a Combined Button and Necktie-Fastener; and I do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to certain new and useful improvements in combined button and necktie-fasteners; and it has for its object to generally improve upon the construction of this class of devices, and at the same time to 20 render the same more efficient and serviceable in operation.

To these ends, and to such others as the invention may pertain, the same consists in the peculiar construction and in the novel combination, arrangement, and adaptation of parts, all as more fully hereinafter described, shown in the accompanying drawings, and then specifically defined in the appended 25 claim.

30 The invention is clearly illustrated in the accompanying drawings, which, with the letters of reference marked thereon, form a part of this specification, like letters of reference indicating like parts throughout the several 35 views, and in which drawings—

Figure 1 is a perspective view of a combined button and necktie-fastener constructed in accordance with my invention. Fig. 2 is a central vertical section through the device and the 40 necktie secured in place by the fastener. Fig. 3 is an enlarged detail of the button, and Fig. 4 is a similar view of the necktie-securing attachment separated from the button. Fig. 5 is a plan view of the strip from which the tie- 45 fastener is made.

Reference now being had to the details of the drawings by letter, A designates the disk

or head of the button, and B the shank, said shank being of flat or sheet metal of suitable width and thickness, and is provided at a 50 point near its outer end with an opening C.

The necktie-fastener attachment D is made of a single strip of sheet metal bent, as shown, to form the hook E, and again bent at E' to form the lateral arm F upon the rear face of 55 the hook and extending at right angles to the body of the same. From the angle at which the arm F unites with the hook the rear face of the hook is provided with a longitudinal slit G, which slit extends to the bottom of the 60 hook, thus separating from the back of the hook the strip H, which strip is bent outwardly to form the arm I parallel with the arm F, and both of said arms are sharpened at their ends, as shown, so as to permit of 65 their being readily inserted into the necktie when in use.

The operation of the device will be readily understood. The shank of the button is passed outwardly through the button-hole 70 upon the shirt. The arms F and I of the retaining attachment are passed through the back of the necktie and are bent downwardly, as shown in Fig. 4, after which the hook E is engaged with the opening C in the outer end 75 of the shank of the button.

Having thus described my invention and set forth its merits, what I claim to be new, and desire to secure by Letters Patent, is—

80 A necktie-fastener attachment consisting of a single piece of metal bent to form a hook, a lateral prong F, extending from a portion parallel with the said hook, and a lateral prong I, extending substantially parallel with the prong F, said fastener being adapted to 85 be secured to a tie and the hook portion to engage the apertured shank of the button, substantially as shown and described.

In testimony whereof I affix my signature in presence of two witnesses.

THOMAS K. CONWAY.
